United States Patent Office

Des. 182,066
Patented Feb. 11, 1958

182,066

PISTOL

Warren N. Fetty, Altadena, and Arthur K. Melin,
Pasadena, Calif.

Application November 28, 1955, Serial No. 39,058

Term of patent 7 years

(Cl. D30—1)

FIG. 3.

FIG. 2.

FIG. 1.

FIG. 4.

FIG. 5.

FIG. 6.

Fig. 1 is a top plan view of a pistol showing our new design;

Fig. 2 is a side elevational view of the pistol;

Fig. 3 is a front elevational view of the pistol;

Fig. 4 is a view of the side opposite that shown in Fig. 2;

Fig. 5 is a rear elevation of the pistol; and

Fig. 6 is a bottom plan view of the pistol.

We claim:

The ornamental design for a pistol, as shown.
